UNITED STATES PATENT OFFICE

ALBERT BENNINGTON, OF RIDLEY PARK, PENNSYLVANIA

PORTABLE BLACKBOARD RENOVATOR

Application filed July 9, 1928. Serial No. 291,187.

My invention relates to new and useful improvements in a portable blackboard renovator, and has for one of its objects to vary or improve the construction of a similar device illustrated in my Patent No. 1,582,664, dated April 27, 1926, and the cleaning heads illustrated in Patents Nos. 1,628,520 and 1,628,521, dated April 5, 1927.

Another object of my invention is to provide a cleaning head wherein the abrasive surfaces travel parallel with the axes of the supporting medium.

Another object of the invention is to provide two abrasive surfaces, the effective portions of which are in parallelism and moving toward each other in order to overcome the tendency to travel along the surface being cleaned as occurs when but a single revolving abrasive surface is used. By overcoming this tendency to travel, the labor of the operator is greatly reduced.

Another object of the invention is to provide a cleaning head comprising a suitable casing in which are mounted a pair of revoluble rollers for the reception of abrasive material, said rollers being arranged in parallelism and having means in one portion or compartment of the casing for revolving said rollers in unison in opposite directions so that their effective working faces are moving toward each other.

A further object of the invention is to provide a simple, effective and improved means for detachably or temporarily securing sheets of abrasive material on the rollers.

A further object of the invention is to provide a blackboard renovating machine comprising a cleaning head including abrasive means for grinding off foreign substances and possibly portions of the blackboard surface in conjunction with means for sucking dislodged material into the head and conveying it to a place of disposal.

With these ends in view, this invention consists in the details of construction and combination of elements hereinafter set forth and then specifically designated by the claims.

In order that those skilled in the art to which this invention appertains may understand how to use and make the same, I will

describe its construction in detail, referring by numerals to the accompanying drawings, forming a part of this application, in which:

Fig. 1 is a side elevation of a portable blackboard renovator constructed in accordance with my improvements, portions of which are broken away and shown in section to illustrate certain details. 55

Fig. 2 is a plan view thereof. 60

Fig. 3 is an end view of the Y-shaped union through which the motor shaft and the refuse conduit are connected with the cleaning head. 65

Fig. 4 is a plan view thereof showing a part of the motor to which it is connected. 70

Fig. 5 is a side elevation of Fig. 4. 75

Fig. 6 is a longitudinal sectional view thereof with parts left in elevation. 80

Fig. 7 is an end view opposite to that shown in Fig. 3. 85

Fig. 8 is an enlarged view of the head with the closure plate or cover removed. 90

Fig. 9 is a section on the line 9—9 of Fig. 10. 95

Fig. 10 is a section on the line 10—10 of Fig. 8, with the shafts and gearing left in elevation. 100

Fig. 11 is a section on the line 11—11 of Fig. 10. 105

Fig. 12 is a view looking into the mouth of the cleaning head with one of the rolls and component parts partly broken away to illustrate structural details. 110

Fig. 13 is an end view of one of the rollers carrying the abrasive substance and illustrating the manner in which the sheet of abrasive material is held in place. 115

Fig. 14 is a similar view with the clamping rod removed. 120

Fig. 15 is an end view of the cleaning head opposite to that illustrated in Fig. 8. 125

In carrying out my invention as herein embodied, 20 represents a suitable base support for the apparatus and by which it may be moved about from place to place as the work progresses and on this base support is mounted a tubular standard 21 for the reception of the extension rod 22 which telescopes in the member 21. On top of the extension rod 22 130

is mounted a table 23 to support a motor 24.

The table is also provided with a bracket 25 and to this is fastened the suction device 26 herein illustrated as a suction fan which is driven from the motor through the medium 6 of a belt 27 running over a pulley 28 on the fan shaft and another pulley 29 on one end of the motor shaft.

The suction device discharges through the outlet or exhaust 30 from which it may be directed to any desirable place of disposal for the solid particles as to a bag 31 removably mounted upon the exhaust or outlet.

To the inlet of the suction device is connected one end of a conduit 32, the other end of said conduit being attached to the branch 33 of the Y-shaped union or fitting 34, while the other branch 35 of said union is clamped about the bushing 36 surrounding the outer end of the motor shaft 37 as plainly shown in Fig. 6. Both of the branches 33 and 35 extend from the body 38 of the Y-shaped coupling and to said body is attached one end of the flexible tube or conduit 39 which in turn is connected at its outer free end with the cleaning head 40 to be presently described.

In order to support the flexible conduit 39 and component parts adjacent its point of connection with the Y-shaped union so as to reduce to a minimum the possibility of the parts being damaged or broken, I provide a hanger 41 which is carried by or attached to the motor or some other suitable rigid portion of the machine and this hanger extends out a desirable distance beyond the connection between the conduit 39 and the Y-shaped union where it may be provided with a hook 42 for the reception of one end of an elastic or resilient suspending member 43, such as a spring, while the other end is attached to the conduit 39.

To the outer end of the motor shaft 37 is connected one end of a flexible shaft 44 in any suitable or well-known manner and said flexible shaft passes through the branch 35 and the body 38 of the Y-shaped union and then through the flexible conduit 39 and has a tubular connector 44' thereon for detachable connection with a shaft splice 55 for coaction 50 with the stub shaft splice 56 and the complete shaft thus formed is journalled in suitable ball bearings 57 and 58 carried by the barrel 59 set between the ribs 60 projecting from the inner surface of the neck 61 of the casing 62 to be hereinafter more fully described. The tubular connector 44' has an external groove 44" which acts as a conveyor to urge any material outward that might otherwise tend to enter the bearings.

The flexible shaft is generally enclosed in a flexible lattice-like sheath 63, Fig. 6, and said sheath is provided with a tubular terminal 64, Fig. 10, detachably connected with the reducing coupling 65 which in turn is detachably connected with the inner end of the

barrel 59 and the other end of said sheath is connected to the bushing 36, Fig. 6.

The cleaning head casing 62 is divided transversely into a primary section 66 with which the neck 61 is formed and a secondary 70 detachable section 67, the latter being held on the former by the screws 68 having threaded connection with the thick end wall and also by screws 69 having threaded connection with flanges 70 and 71 formed with the sections 66 75 and 67 respectively at the opposite end.

The interior of the cleaning head casing is divided into two main compartments, the larger one of which is represented by the numeral 72 and will be known as the roller compartment, while the other compartment 73 holds a train of gears and as will be obvious these compartments are formed by both of the sections 66 and 67.

In the roller compartment are located in 85 parallel relation two rollers 74 and 75 mounted on shafts 76 and 77 respectively journalled in suitable ball bearings, indicated in dotted lines in the several views which are recessed in the thick end wall of the cleaning head casing and the flanges formed with the casing sections. On the roller shafts are fixed gears 78 and 79, the former meshing with a gear 80 while the latter meshes with an idler gear 81 also meshing with the gear 79. 95

The gears 80 and 81 are mounted on suitable shafts 82 and 83 respectively which are suitably journalled, the shaft 82 being shown as journalled in ball bearings 84 and 85 recessed in an enlargement or rib 86 through which said shaft 82 passes, said rib being located on the longitudinal center line of the cleaning head casing.

The shaft 82, on the outer end of which is mounted the gear 80, has a bevel gear 87 mounted on its inner end and meshing with a bevel gear 88 mounted on the stub shaft splice 56. 105

The upper end of the barrel 59 and the contiguous end of the rib 86 are normally closed by a removable cap 89 in order to exclude foreign matter from the gears and bearings and the gear compartment 73 is normally closed by a closure plate 90 held in place by screws 91. 110

From the above, it will be obvious that when the flexible shaft 44 is revolved in the proper direction, motion will be transmitted through the gears 88 and 87 and the shaft 82 of the latter to the train of gears at one end 120 of the cleaning head casing and through them to the rollers 74 and 75 so that said rollers will be revolved in opposite directions and their outer working surfaces revolved toward each other so that during use of the device, the motion of one roller tends to counter-balance that of the other making it much easier for the operator to handle the cleaning head and hold it in any one place or move it about as desired. 125

Each roller has a longitudinal slot 92 in its outer surface and communicating with a longitudinal tapered hole 93 whereby the ends of a sheet 94 of abrasive material may be inserted through the slot into the tapered hole and thereafter a tapered pin 95 inserted in the tapered hole so as to clamp the inserted ends of the abrasive sheet between said pin and the walls of the roller forming the tapered hole and in actual practice, it has been found that as the tapered pin is inserted, the abrasive sheet is drawn taut about the periphery of the roller.

In order to hold the tapered pin in place and also draw it into its final position, said pin is provided with a head 96 in the form of a plate which may be secured to the larger end of the pin by a screw 97 and the ends of said plate 96 are provided with apertures for the reception of screws 98 which are threaded into the roller on both sides of the slot and as they draw said plate into the recess 99, the pin 95 will be forced into the tapered hole.

In order to have access to the screws 98 and to permit the removal and replacement of the tapered pin without having to disassemble the parts of the cleaning head, the flange end wall of the section 67 is provided with recesses 100 in its upper edge with which the pins and their heads may align when the rollers are rotated to the proper positions.

In operation, when the motor 24 is running the suction device 26 will produce a current of air through the tube or conduit 39 and the cleaning head, and at the same time the flexible shaft will be revolved for transmitting power and motion to the rollers carrying the abrasive material. By moving the cleaning head with the rollers, or more particularly the abrasive material thereon, in contacting with a blackboard surface, the foreign material such as the accumulation of grease will be ground away and since the rollers are revolved toward each other, the tendency will be to throw the particles dislodged from the blackboard surface into the cleaning head between said rollers where they will be transported by the current of air through the conduit 39 to the Y-shaped union 34 and thence through the branch 33 of said union to the conduit 32 and through the latter and the suction of device 26 into the bag or other receptacle 31.

Because of the swivel connection between the neck 61 of the cleaning head and the sleeve 101 over which one end of the conduit 39 is slipped and by means of the union nut 102, said cleaning head may be readily rotated about the axis of its neck permitting the machine to grind closer to the blackboard molding than would be the case if the head had to be always held in one position. This makes it possible to machine-clean a greater area of

the blackboard and reduces the hand operation to a considerable extent.

Of course I do not wish to be limited to the exact details of construction as herein shown, as these may be varied within the limits of the appended claims without departing from the spirit of my invention.

Having thus fully described my invention, what I claim as new and useful is:

1. In a device of the character described, a cleaning head having a large and small compartment therein, a neck formed with the head, a sleeve swiveled to the neck, a split shaft mounted in the neck, a flexible shaft positioned in the sleeve and removably connected to the split shaft, a beveled gear carried by the upper end of the split shaft, a second beveled gear meshing with the first named beveled gear, a driving shaft upon which the second named beveled gear is secured, a driving gear secured upon said driving shaft and located within the small compartment of the cleaning head, a driven gear wheel meshing with the driving gear wheel, a shaft upon which the driven gear wheel is mounted, an abrasive roll mounted upon said shaft within the large compartment, a second shaft journaled in the head, a second abrasive roll mounted thereon, and a pinion meshing with the last named gear wheel and the driving gear wheel.

2. In a device of the character described, a cleaning head made in two sections and having a large and small compartment therein, a pair of abrasive rolls mounted in the large compartment, a train of gears mounted in the small compartment adapted to revolve the rolls in reverse directions, a neck formed with the head, a sleeve with which said neck is swivelly connected, ribs formed upon the inner surface of the neck, a barrel positioned between said ribs, a stub shaft journaled in the barrel, a splice shaft coating with the stub shaft for providing a slipped action, a beveled gear carried by the upper end of the stub shaft, a second beveled gear meshing with the first named beveled gear, a driving shaft upon which the second named beveled gear is mounted, said driving shaft having mounted upon its outer end the driving gear of said train of gears, means for revolving the splice shaft, and means for sucking air from the large compartment.

3. In a device of the character described, a cleaning head having a large and a small compartment therein, a neck formed with the head, a hollow enlargement having one end adjacent to the inner end of the neck and communicating with the smaller compartment, a barrel of smaller diameter than the neck and mounted therein, means common to the barrel and hollow enlargement for closing the space between said neck and hollow enlargement whereby an enclosed communication is formed between the barrel and hol-

- low enlargement, a pair of abrasive rolls mounted in the larger compartment, a train of gears mounted in the smaller compartment adapted to revolve the rolls in reverse directions, a prime mover, mechanism for transmitting motion from said prime mover to the train of gears, a portion of said means being located in the barrel and the hollow enlargement, a suction device driven by the prime mover, and means to connect said suction device with the neck of the cleaning head for drawing material dislodged by the rolls from the larger compartment through the neck.
4. A device of the kind described including a head having two compartments, a neck formed with said head and communicating with one of the compartments therein, means to provide an enclosed passage-way through the neck and the compartment with which said neck communicates to the other compartment in said head, a pair of rollers journaled in the compartment with which the neck communicates, a train of gears mounted in the other compartment for revolving said rollers in reverse directions, and mechanism in the enclosed passage-way for transmitting motion from a prime mover to the train of gears.

In testimony whereof, I have hereunto affixed my signature.
